Des. 1337

Samuel H. Sailor & Jacob Steffe, of Philadelphia, Penn.
Assignors to North, Chase & North, of same places
Letters Patent No. 1337. Dated Oct. 9, 1860.

The schedule referred to in these Letters Patent and making part of the same

To all whom it may concern:

Be it known that we, Samuel H. Sailor and Jacob Steffe, of the City and County of Philadelphia, and State of Pennsylvania, have invented or produced a new and original design for Stoves, and we do hereby declare that the following is a full and exact description of the same, reference being had to the accompanying drawings, in which:

- Fig: 1. represents, a front bottom plate or ash pit.
2. " " , an upper front plate,
3. " " , an oven door.
4. " " , a fire door.
a, b, c, d. are mouldings.

What we claim as our invention and desire to secure by Letters Patent, is the design and configuration of the mouldings and ornaments, as herein described, forming an ornamental design for Stoves.

End Witnesses.
